UNITED STATES PATENT OFFICE.

GEORGE A. TUCK, OF SAN FRANCISCO, CALIFORNIA.

AUTOMATIC FLUE CONTROL FOR FURNACES.

Application filed January 10, 1927. Serial No. 160,107.

My improvement relates to improvements in gas furnaces and more particularly to flue controlling means for furnaces whereby the passage of combusted gases to a chimney 5 may be automatically regulated to prevent condensation within the furnace and to regulate stack temperature and to give increased efficiency.

One of the most important problems to be met in the construction and operation of gas furnaces and the like, is to overcome the condensation of gaseous products of combustion within the combustion chamber and flues of the furnace when the fuel is first ignited and 10 before the furnace has become fully heated. This condensation is extremely objectionable, as the nature of the condensation is such as to very rapidly corrode the walls and partitions of the furnace and greatly shorten the 15 life of the furnace. The primary object of the present invention is therefore to provide an improved furnace having means for preventing condensation within the furnace.

Another important problem is to obtain an 20 efficient combustion during the initial heating of the furnace. The tortuous passages commonly provided within such furnaces and the ordinary construction and arrangement of the combustion chambers and flues is such 25 that when fuel is first ignited within a cold furnace the draft and circulation is very poor and as a result the flame is choked and sometimes entirely extinguished. If the initial draft is made sufficient to obtain an efficient 30 combustion the draft is subsequently increased to such an extent as to greatly reduce the normal operating efficiency. The partial choking of the flame increases the condensation within the furnaces above mentioned and 35 is further objectionable for that reason. It is therefore another important object of the present invention to provide an improved furnace in which efficient combustion may be obtained when the fuel is first ignited and 40 which will maintain a maximum efficiency during normal operation after the furnace has become heated.

A further object is to provide an improved furnace wherein the passage of combusted 45 gases to the chimney is automatically regulated to maintain a desired stack temperature and to obtain increased heating efficiency.

Another object is to provide an improved flue regulating means which is extremely simple in construction and efficient in operation and which may be easily installed.

A still further object is to provide an improved flue regulating means which is entirely automatic in its operation and which may be easily adjusted to meet the requirements of each particular installation. 60

I accomplish these and other objects by means of the improved device disclosed in the drawings forming a part of the present application wherein like characters of reference 65 are used to designate similar parts throughout the specification and drawings, and in which:

Fig. 1 is a broken vertical section of the 70 improved furnace.

Fig. 2 is a broken sectional detail drawn upon a larger scale showing the manner in which air is admitted into the combustion chamber.

Fig. 3 is a longitudinal vertical section of 75 the vent passage and flue regulating means mounted therein.

Fig. 4 is a longitudinal horizontal section of the vent passage and regulating means as shown in Fig. 3. 80

Fig. 5 is an elevation of the inner end of the members shown in Figs. 3 and 4, parts being broken away.

Fig. 6 is a sectional detail of the by-pass connection and its damper. 85

Referring to the drawings the numeral 1 is used to designate the outer housing shell of a furnace provided with a combustion chamber 2 having a suitable burner 3 mounted within the bottom thereof and connected 90 at its upper end with a tortuous flue passage indicated in general by the numeral 4. Air is supplied around the burner 3 through an air passage 6 formed in the bottom of the combustion chamber 2 by means of a partition 7, 95 the air being admitted into the combustion chamber through an opening 8 formed around the outer side of the combustion chamber. Air is admitted into the passage 6 through an inlet 9 provided with a pair of doors 11 arranged to be moved to obtain a desired opening whereby the amount of air admitted may be regulated as desired. The flue passages 4 are arranged inside of the combustion chamber 2 and preferably consist of an outer portion 4 and an inner portion 4', the outer portion 4 communicating with the chamber 2 through passages 12 and 100 communicating with the inner portion 4' through passages 13.

A vent member designated in general by the numeral 14 is mounted above the combus- 110

tion chamber 2 and connected at its inner end to the inner flue portion 4'. A by-pass 16 is connected between the vent member 14 and the combustion chamber 2. The outer end of the vent member is closed by means of a suitable cap 17 and is provided with an upwardly disposed lateral outlet 18 arranged to be connected to a suitable chimney 19.

The by-pass member 16 extends upwardly into the vent member 14 and is arranged to receive a collar 21 upon which is mounted a diametrically disposed shaft 22. A damper 23 is secured upon the shaft 22 and arranged to be moved to fully close the by-pass 16, one edge of said damper being arranged to seat upon the upper edge of the collar 21 while the opposite edge is arranged to seat against the under side of a flange 24 secured upon the top of the collar.

20 The shaft 22 is carried by suitable bearings formed upon the top of the collar 21. The inner end of the shaft is extended inwardly and is provided with a damper 26 adjustably secured upon the end of the shaft.

25 The damper 26 is preferably made of a plurality of overlapping sectors arranged to be adjusted relative to each other to obtain a desired damper area, said damper 26 being positioned in proximate relation to a partition 27 secured within the lower portion of the vent member 14. The vent member 14 is made of sufficient diameter to permit the collar 21 and the shaft 22 and dampers 23 and 26 carried thereby to be inserted through 30 the outer end of the member and fitted as a unit upon the top of the by-pass 16. The partition 27 reduces the area of the passage through the vent member to a desired maximum.

35 40 The shaft 22 and the dampers carried thereby are actuated thermostatically by means of a spiral spring 28 formed from suitable metal, said spring having its inner end secured upon the shaft 22 and its outer end secured upon an arm 29 secured upon the collar 21, said spring being so designed that the expansion resulting from heating the spring to a predetermined temperature will operate to partially rotate the shaft 22, and thereby move 45 the dampers 23 and 26 into closing relation with the by-pass 16 and the opening through the vent member 14 past the partition 27.

50 55 In operation, the spring 28 is arranged to hold the damper 23 in fully open position at ordinary room temperatures. When fuel, delivered through the burner 3, is ignited within the combustion chamber, the chamber 2 will be heated almost at once to its full operating temperature and the products of combustion may pass directly from the chamber 2 through the by-pass 16 and thence through the vent member 14 to the chimney 19. The damper 26 is so adjusted upon the shaft 22 that it will be disposed directly in back of 55 the partition 27 and form no obstruction to

the passage through the vent member 14 past said partition 27. This permits a maximum draft to be obtained through the flue portion 4 and 4' so that while the major portion of the products of combustion pass directly through the by-pass 16, a relatively small portion will be drawn through the flue 4. The burner of course generates its full heat as soon as the gaseous fuel is ignited and the combusted gases passing directly upwardly through the by-pass 16 to the chimney cause the vent member 14 and chimney to be quickly heated to a relatively high temperature. At the same time, the small amount of combusted gas passing through the flue 4, together with the heat radiated from the chamber 2, causes the flue portions 4 and 4' to be gradually heated to a degree such that condensation will not occur.

55 60 When the vent member 14 and chimney 19 have been raised to a predetermined degree of temperature, the resulting expansion of the spring 28 within the member 14 causes the shaft 22 to be rotated sufficiently to move the damper 23 into closed relation with the by-pass 16. All the products of combustion must now pass through the flue 4 which by this time will have been heated to such a degree that an efficient draft will be produced, and condensation cannot occur. At the same time, the rotation of the shaft 22 causes the damper 26 to be moved to partially obstruct the passage through the vent member 14 past the partition 27, as shown on the dotted lines in Fig. 5 of the drawings. The damper 26 is made of sectors relatively adjustable to obtain a desired area, and the damper is also made adjustable relative to the shaft so that the movement imparted by the shaft 22 will cause the damper to obstruct a desired portion of the space above the partition 27 and thereby reduce the draft to a degree calculated to maintain a desired chimney or stack temperature and obtain a maximum heating efficiency from the fuel. The adjustment of the damper 26 is 65 dependent upon prevailing conditions and must be determined for each particular installation. The restriction to the draft which is thus obtained prevents excessive dilution of the combusted gases by cold air drawn from outside of the furnace, and permits the normal draft to be reduced to a degree adapted to give the maximum heating efficiency. The outside air drawn into the combustion chamber to maintain combustion 70 is admitted from the outside of the burner through the opening 8 so that such air must necessarily cross over the burner and be heated before passing into the flue 4.

75 80 While I have illustrated my improved automatic flue control as applied in its proposed form, in connection with a furnace of one particular form, the control may of course be applied to furnaces of various other types, and intended for use with various fuels, wherein it 85

is desired to divert the products of combustion from one to another of two or more vent passages to vary the draft and regulate stack temperature. I, therefore, do not wish to restrict myself to the specific furnace construction illustrated nor to the particular form and arrangement of the control elements shown and described, but desire to avail myself of all modifications in form, arrangement, and construction which may fall within the scope of the appended claims.

Having thus described my invention, which I claim as new and desire to secure by Letters Patent is:

15 1. A gas furnace comprising a combustion chamber and flue; a vent passage communicating with the chamber and flue through openings arranged at spaced points along said chamber and flue; and means for automatically closing one of said openings and for restricting another opening when the temperature of gases within the vent passage reaches a predetermined degree.

25 2. A furnace comprising a combustion chamber and flue; a chimney; a vent passage connecting the flue and the chimney; a by-pass directly connecting the vent passage and the combustion chamber; and means entirely enclosed within the vent passage for automatically closing the by-pass when the temperature of gases within the vent passage reaches a predetermined degree.

35 3. A furnace comprising a combustion chamber and flue; a chimney; a vent passage connecting the flue and the chimney; a by-pass connecting the vent passage and the chamber; means for automatically closing the by-pass when the temperature of gases within the vent passage reaches a predetermined degree; and means connected to the by-pass closing means and actuated therewith for restricting the passage between the flue and chimney.

45 4. A furnace comprising a combustion chamber and flue, a chimney; a vent passage connecting the flue and the chimney; a by-pass connecting the vent passage and the chamber; means for automatically closing the by-pass when the temperature of gases within the vent passage reaches a predetermined degree; and adjustable means connected to the by-pass closing means and actuated therewith for restricting to a desired degree the passage between the flue and chimney, when the by-pass is closed.

55 5. A gas furnace comprising a combustion chamber, a tortuous flue connected to the combustion chamber; a chimney; a vent passage connecting the chimney and the flue; a by-pass directly connecting the combustion chamber and the vent passage; and means for automatically closing the by-pass by an increase in temperature of gases within the vent passage when said temperature reaches a predetermined degree.

65 6. A gas furnace comprising a combustion

chamber; a tortuous flue connected to the combustion chamber; a chimney; a vent passage connecting the chimney and the flue; a by-pass directly connecting the combustion chamber and the vent passage; means enclosed within the vent passage for automatically closing the by-pass when the temperature of gases within the vent passage reaches a predetermined degree; and means connected to the by-pass closing means and actuated therewith for restricting the passage between the flue and the chimney.

70 7. A gas furnace comprising a combustion chamber; a tortuous flue connected to the combustion chamber; a chimney; a vent passage connecting the chimney and the flue, a by-pass directly connecting the combustion chamber and the vent passage; a damper mounted in connection with the by-pass; and thermostatic means enclosed within the vent passage for moving the damper to close the by-pass when the temperature of gases within the vent passage reaches a predetermined degree.

75 8. A gas furnace comprising a combustion chamber; a tortuous flue connected to the combustion chamber; a chimney; a vent passage connecting the chimney and the flue; a by-pass connecting the combustion chamber and the vent passage; a damper mounted in connection with the by-pass; thermostatic means enclosed within the vent passage for moving the damper to close the by-pass when the temperature of gases passing through the tortuous flue and the vent passage reaches a predetermined degree; and a vent damper connected to the by-pass damper and actuated therewith for restricting the vent passage when the by-pass is closed.

90 105 9. A gas furnace comprising a combustion chamber; a tortuous flue connected to the combustion chamber; a chimney; a vent passage connecting the chimney and the flue; a by-pass connecting the combustion chamber and the vent passage; a damper mounted in connection with the by-pass; thermostatic means enclosed within the vent passage for moving the damper to close the by-pass when the temperature of gases passing through the tortuous flue and the vent passage reaches a predetermined degree; and an adjustable vent damper connected to the by-pass damper and actuated therewith for restricting to a desired degree the vent passage when the by-pass is closed.

110 115 120 125 130 10. In a furnace; the combination with a combustion chamber and flue of a vent passage having openings communicating with said chamber and flue at spaced points; a damper pivotally mounted adjacent one of said openings; a vent damper connected to the first mentioned damper; and thermostatic means for automatically actuating both dampers simultaneously to close one opening and to restrict the vent passage when the

temperature of gases within said passage reaches a predetermined degree.

11. In a furnace; the combination with a combustion chamber and a flue of a vent passage having a main opening communicating with the flue and a by-pass opening communicating with the chamber; a damper pivotally mounted adjacent the by-pass opening; an adjustable vent damper mounted within the vent passage and connected with the by-pass damper; and thermostatic means for automatically moving the dampers to close the by-pass and restrict the vent passage when the temperature of gases within said vent passage reaches a predetermined degree.

12. A gas furnace comprising a combustion chamber; a tortuous flue connected to the combustion chamber; a chimney; a lateral vent passage connecting the flue and the chimney; a by-pass connected directly from the top of the combustion chamber into the vent passage; and means mounted in connection with the upper end of the by-pass and enclosed within the vent passage for automatically closing the by-pass and restricting the vent passage when the temperature of gases passing outwardly to the chimney reaches a predetermined degree.

13. A gas furnace comprising a combustion chamber; a tortuous flue connected to the combustion chamber; a chimney; a lateral vent passage connecting the flue and the chimney; a by-pass member connected directly from the top of the combustion chamber into the vent passage, the upper end of the by-pass member extending into the vent passage; a collar mounted upon said upper end of the by-pass member; a damper mounted upon the collar; and thermostatic means enclosed within the vent passage for automatically closing the by-pass when the temperature of gases passing outwardly to the chimney reaches a predetermined degree.

14. A gas furnace comprising a combustion chamber; a tortuous flue connected to the combustion chamber; a chimney; a lateral vent passage connecting the flue and the chimney; a by-pass member connected directly from the top of the combustion chamber into the vent passage, the upper end of the by-pass member extending into the vent passage; a collar mounted upon said upper end of the by-pass member; a damper mounted upon the collar; and thermostatic means enclosed

within the vent passage for automatically closing the by-pass when the temperature of gases passing outwardly to the chimney reaches a predetermined degree; and a damper mounted within the vent passage and actuated in connection with the by-pass damper for restricting the vent passage when the by-pass is closed.

15. A gas furnace comprising a combustion chamber; a tortuous flue connected to the combustion chamber; a chimney; a lateral vent passage connecting the flue and the chimney; a by-pass member connected directly from the top of the combustion chamber into the vent passage, the upper end of the by-pass member extending into the vent passage; a collar removably mounted upon said upper end of the by-pass member; a damper mounted upon the collar; and thermostatic means enclosed within the vent passage and mounted in connection with the collar and by-pass damper for automatically closing the by-pass when the temperature of gases passing outwardly to the chimney reaches a predetermined degree, said means being removable from the vent passage with the collar and damper.

16. A gas furnace comprising a combustion chamber; a tortuous flue connected to the combustion chamber; a chimney; a lateral vent passage connecting the flue and the chimney; a by-pass member connected directly from the top of the combustion chamber into the vent passage, the upper end of the by-pass member extending into the vent passage; a collar removably mounted upon said upper end of the by-pass member; a damper mounted upon the collar; and thermostatic means enclosed within the vent passage and mounted in connection with the collar and by-pass damper for automatically closing the by-pass when the temperature of gases passing outwardly to the chimney reaches a predetermined degree, said means being removable from the vent passage with the collar and damper; and an adjustable damper mounted in connection with the by-pass damper and removable therewith from the vent passage for restricting the vent passage simultaneously with the closing of the by-pass damper.

In witness whereof I hereunto set my signature:

GEORGE A. TUCK.
